CLAIM

The ornamental design for combined golfer's green repairer, shoehorn, cleat tightener and cleaner, and golf club and cigarette rest, as shown.

DESCRIPTION

FIG. 1 is a perspective view of a combined golfer's green repairer, shoehorn, cleat tightener and cleaner, and golf club and cigarette rest showing my new design. FIG. 2 is a top plan view thereof.

FIG. 3 is a side elevation view thereof.

FIG. 4 is a bottom plan view thereof.

FIG. 5 is a front end view thereof.

FIG. 6 is a rear end view thereof.
